UNITED STATES PATENT OFFICE

98,092

DESIGN FOR A POWDER BOX OR SIMILAR ARTICLE

Jacob S. Sherman, Chicago, Ill.

Application November 11, 1935, Serial No. 59,496

Term of patent 14 years

To all whom it may concern:

Be it known that I, Jacob S. Sherman, a citizen of the United States and resident of Chicago, in the county of Cook and State of Illinois, have invented a new, original, and ornamental Design for a Powder Box or Similar Article, of which the following is a specification, reference being had to the accompanying drawing, forming a part thereof.

Figure 1 is a top plan view of a powder box or similar article showing my new design;

Fig. 2 is an elevational view; and
Fig. 3 is a bottom plan view.

I claim:

The ornamental design for a powder box or similar article, substantially as shown.

Signed at Chicago, in the county of Cook and State of Illinois, this 8th day of November, 1935.

JACOB S. SHERMAN.
